Primary Examiner — T Chase Nelson

Assistant Examiner — Sydney Margaret Parsley

(57) **CLAIM**

The ornamental design for a ladder top cap bucket as shown and described.

DESCRIPTION

FIG. 1 is a perspective view of a ladder top cap bucket showing our new design;

FIG. 2 is a top view thereof;

FIG. 3 is bottom view thereof;

FIG. 4 is a front elevational view thereof;

FIG. 5 is a rear elevational view thereof;

FIG. 6 is a right-side elevational view thereof; and,

FIG. 7 is a left-side elevational view thereof.

The broken lines shown in the figures define the bounds of the claimed design and form no part of the claimed design.

1 Claim, 7 Drawing Sheets
